MATRIX-SETTING AND TYPE-LINE-CASTING MACHINE

Julius Dorneth, Konradshohe, near Tegel, Germany, assignor to Typograph G. m. b. H., Berlin, Germany

Application May 22, 1933, Serial No. 672,334
In Germany September 24, 1932

3 Claims. (Cl. 199—25)

The invention relates to a key mechanism for matrix-setting and type-line-casting machines, and more particularly a mechanism in which, after striking the keys, the subsequent matrix releasing operation is effected by power drive. Normally, in such key mechanisms, the matrix releasing devices are connected to the free ends of double levers, the other ends of which rest on supporting elements moved by the keys. On depressing a key, that end of the lever which faces it moves downwardly, whereby the subsequent mechanical release is rendered possible. Discs mounted eccentrically on the releasing levers and adapted to rotate easily are usually employed for this purpose, and these discs are released on the aforesaid movement of the releasing levers and by their toothed periphery engage continuously rotating rubber rollers driven by the machine, so that due to their eccentric mounting, the said discs turn the arms of the releasing levers, carrying them upwardly beyond their inoperative position, whereby the associated matrices are released. As the compositor, when setting type, only strikes one key after the other, the matrices are only released one after the other in this sequence. If, however, a number of keys are depressed unintentionally on the inoperative machine, for example by unauthorized persons, and the corresponding eccentric discs are consequently brought into engagement with the rubber rollers, then, on starting up the machine, the associated matrices, which are not necessary for the composition, will first be released simultaneously. For the purpose of preventing stoppages and damage to the matrices caused thereby, it is known to secure the releasing levers or the eccentric discs in their inoperative position by inserting a special locking bar in the key mechanism after stopping the machine. The said locking bars which are separate from the machine are about the length of the entire key mechanism. In the case of brief working pauses, therefore, the known device is hardly ever used in practice.

It has also been attempted to incorporate rotatable locking bars in the key mechanisms, but such locking bars all suffer from the disadvantage that they lock not only the releasing levers but also the keys themselves, whereby damage may easily be caused to parts of the key mechanism if, in an unforeseen manner, more than the normal pressure is exerted upon the locked keys. In addition, unauthorized persons interfering with the key mechanism will thus readily notice the

locking means and be induced to render them inoperative.

The present invention consists in the fact that the rotatable locking bars incorporated in the key mechanism secure the releasing levers with the eccentrics in the inoperative position without the keys themselves being locked. The aforesaid disadvantages are thereby eliminated, and over and above this it is possible to allow an apprentice compositor to carry out under normal working conditions on the machine itself the setting or key exercises which are indispensable for him, without for instance the necessity for the separate key mechanisms frequently employed heretofore for such purposes.

A constructional example of the invention is shown diagrammatically in the accompanying drawing, wherein:

Figure 1 is a side elevation of the key mechanism in part section, and

Figure 2 shows a partial section along the line II—II in Figure 1.

The releasing levers 3 are rotatably mounted on a spindle 2 in the casing 1 of the key mechanism. The free ends of the levers 3 are connected by means of members 4 (wires, rods, Bowden (registered trade-mark) cables) to the matrix releasing devices not shown. Those ends of the releasing levers 3 which face the keys 5 rest on supporting elements 6 moved by the keys 5. The discs 8 provided with teeth on their periphery and adapted to turn about a pivot 7 on the lever 3, are mounted eccentrically in known manner so that, on release of those ends of the releasing levers 3 which face the keys 5 being effected by the depression of the said keys, the discs 8 are brought into engagement with the continuously rotating rubber rollers 9 driven by the machine. The eccentric discs 8 are held in their inoperative position preparatory to operation by pins 10 which are mounted on them and which bear against the stops 11, for example the prongs of a spacing comb, fixed in the casing 1 of the key mechanism.

A round or flat locking bar 12 (indicated by dotted lines in Figure 1) is rotatably mounted in the key mechanism casing 1 by means of pivots 13 eccentrically provided on the said bar in such a manner that the said bar, in its position denoted by "A", bears against the releasing levers 3 and even raises them to a very slight extent, while the locking bar 12 in its position denoted by "B" is at a considerable distance from the releasing levers 3 in order to render possible their free movement. If a flat locking bar is em-

ployed instead of a round locking bar 12, the side 5
engaging the levers 3 is preferably considerably
curved to avoid wear on the parts. On one side
of the key mechanism casing 1, a knob or handle
14 is fixed on an extension of the pivot 13, which
handle is operated by the compositor if the lock-
ing bar 12 is to be brought into the one or the
other position. The end positions of the han-
dle 14, corresponding to the positions "A", "B"
10 of the locking bar 12 are secured in any de-
sired manner by stops or resilient catches 15,
16. Instead of the arrangement of the lock-
ing bar 12 as shown in Figure 1, in which the
said locking bar co-operates with those arms of
15 the releasing levers 3 which face away from
the keys 5, it is also possible to mount the
locking bar 12 within the key mechanism, for
instance at the points shown at "C" and "D" in
Figure 1, so as to lock those arms of the releas-
ing levers 3 which carry the eccentric discs 8.
When the locking bar 12 is in its locking posi-
tion, the keys 5 can be depressed unhindered
without the releasing levers 3 and the eccentric
discs 8 moving.

What I claim is:—

1. In a key mechanism for matrix-setting and
type-line-casting machines, matrix releasing le-
vers, operating keys therefor, and a rotatably
operative common locking bar for preventing
the release of the matrices, said locking bar act-
ing solely to hold the releasing levers in the in-
operative position and leaving the keys free for
use in practising.

2. A key mechanism as claimed in claim 1,
wherein eccentric pivots are provided for rotat-
ably mounting the bar and said bar being rounded
at the point which comes into engagement with
the releasing levers.

3. A key mechanism as claimed in claim 1,
wherein eccentric pivots are provided for rotat-
ably mounting the bar and said bar being rounded
at the point which comes into engagement with
the releasing levers, a handle for facilitating
the operation of the locking bar, and catches for
cooperating with the handle in either of its ad-
justed positions.
